UNITED STATES PATENT OFFICE

150,527

DESIGN FOR A LAMP GUARD

Ira E. Wright, Kokomo, Ind., assignor of one-third to Maurice B. Ades and one-third to Lou Marks, both of Louisville, Ky.

Application September 28, 1946, Serial No. 133,637

Term of patent 14 years

(Cl. D48—24)

To all whom it may concern:

Be it known that I, Ira E. Wright, a citizen of the United States, residing at Kokomo, in the county of Howard and State of Indiana, have invented a new, original, and ornamental Design for a Lamp Guard, of which the following is a specification, reference being had to the accompanying drawing, forming part thereof.

The figure is a perspective view of a lamp guard, showing my new design.

I claim:

The ornamental design for a lamp guard, as shown.

IRA E. WRIGHT.
